UNITED STATES PATENT OFFICE.

JOHN ROSCOE MILLWARD, OF NEWARK, NEW JERSEY, ASSIGNOR TO THE DAYTON ENGINEERING LABORATORIES COMPANY, OF DAYTON, OHIO, A CORPORATION OF OHIO.

STARTER FOR INTERNAL-COMBUSTION ENGINES.

1,341,658.

Specification of Letters Patent.

Patented June 1, 1920.

Application filed November 19, 1913. Serial No. 801,850.

To all whom it may concern:

Be it known that I, JOHN ROSCOE MILLWARD, a citizen of the United States, residing at Newark, in the county of Essex and 5 State of New Jersey, have invented new and useful Improvements in Starters for Internal-Combustion Engines, of which the following is a specification.

This invention relates to electrical starting devices for internal combustion engines and controlling means therefor and has particular reference to the coupling means whereby the motor employed is thrown automatically into and out of engagement with 15 the engine to be started.

My improved device is especially adapted for starting automobile engines and an important feature thereof consists in an arrangement whereby the aforesaid means for 20 engaging the motor with the engine controls the current passing through the motor whereby the full working current and the engagement of the connector is made dependent on the proper engagement of the 25 connector and the driving of the engine by the motor. The operation is such that the full working current will not pass through the motor until the gears are in proper mesh and upon the starting of the engine 30 the motor circuit will be opened and the connector disengaged. The latter function is arranged to be effected instantly on the acceleration of the engine by its own power thus to effect the disengagement of the 35 motor before the engine can exert a driving force thereon. My improved arrangement is thus positive in its operation to engage and disengage the motor and, moreover, when disengaged is entirely free of any 40 connection with moving parts.

The foregoing and other features of my invention are shown in the accompanying drawings wherein are shown desirable embodiments of my invention and in which the 45 reference characters of this description are applied to like parts in the various figures.

In the drawings are shown somewhat diagrammatically embodiments of the different features arranged to obtain the characteristic results of my invention. Figure 1 shows a desirable form of my invention wherein the shifting of the connector is effected by a spiral spline or key, the connector being shown in section and in disengaged position. Fig. 2 is a view showing

the same with the connector and switch in position when turning the engine; the connector being here shown in elevation; Fig. 3 is a modified arrangement employing a spiral spline and a shifting armature to 60 effect the initial engagement of the connector. Fig. 4 is an embodiment wherein the complete shifting movement of the connector is effected by the displacement of the armature, the parts being shown in section 65 and in disconnected position. Fig. 5 is a view of the same arrangement when the connector is in engaged position and the current on full. Figs. 6 and 7 are cross-sectional views on line $x-x$ of Fig. 5 illustrating the positions of the contacts when the motor drives the engine and when the engine drives the motor, respectively.

In the figures M indicates the starting motor consisting of an armature 1 carried 75 on a shaft 2 and having the field poles 4-4', commutator 6 and the commutator brushes 7-7'. A suitable frame f is indicated for the purpose of supporting the pole-pieces 4-4' and to provide suitable bearings $b-b$ 80 for the armature shaft 2. The armature shaft is shown elongated at one end to have rotatively secured thereon a shiftable connector element to effect its engagement with the engine to be started, here shown as a 85 driving pinion 8 adapted to engage the gear teeth 10 of the engine fly wheel 12.

The engine is indicated at E and may be the usual internal combustion motor of the automobile type.

In the arrangement of Fig. 1 the pinion 8 is rotatively secured to the armature shaft 2 and laterally shifted thereon by a spiral spline or key-thread 16 formed on an operating collar 18 secured on the shaft end 95 and threaded to the interior of the hub 19 of the connector pinion 8. The motor shown is series wound and the operating circuit is closed therethrough from a storage battery B by a suitable switch arm S. The switch 100 arm, as shown in Fig. 1, is moved to bridge the contacts 21 and 22 initially to close the circuit through the connection 25 having therein a resistance r . The effect thereof will be to energize the motor sufficiently to 105 effect the shifting of the pinion into engagement with the engine gear through the influence of the spiral spline which translates the initial rotative effort of the motor into a lateral shifting of the pinion until 110

in full engagement with the gear 12. When so fully engaged, as indicated in Fig. 2, the hub 19 will engage a stop shoulder 26 on the collar 18 whereby further effort of the motor 5 will rotate the pinion to drive the engine.

Positively to insure shifting of the pinion a retarding spring 28 desirably is arranged to engage the hub 19 of the pinion when current is passed through the connection 25. A magnet 29 wound in series with the connection 25 is then operative to attract its armature 30 carried on the spring 28. The spring is thus drawn downwardly from its normal disengaged position into 15 retarding engagement with the pinion hub thereby insuring the required turning of the operating collar 18 with reference to the pinion to effect the shifting thereof.

Upon the inner end of the pinion hub 19 20 and suitably insulated therefrom is an annular switch member in the form of a copper ring 32 adapted, when the pinion is in full engagement with the gear 12, to engage the brushes 33-34 and close the circuit therethrough to receive the full working 25 current from the battery to turn the engine. The brushes are shown supported by and insulated from the motor frame *f* and connected in series with the motor through the ring 30 32 to a contact 23 likewise engaged by the switch arm *S*.

The switch *S* is indicated to be of rotary type and in Fig. 1 is shown in position closing the circuit through the resistance *r* to effect the engagement of the retarding spring 35 28 and start the motor. The pinion is thereby shifted from the disengaged position of Fig. 1 into the full engagement shown in Fig. 2, closing the work circuit through the 40 ring and the brushes 33-34 whereby the motor is fully energized. Thereafter the motor will operate to turn the engine until the occurrence of the first explosion therein when the engine will immediately increase 45 its speed under its own power. Owing to the lag of the motor the gear 12 will then exert a force on the pinion rotating it at an accelerated speed and with relation to the operating spline whereby it is instantly 50 shifted out of engagement. At the same time it will break the motor circuit through the brushes 33-34 by shifting the ring 32. As the switch *S* will by that time have been advanced to the position of Fig. 2 the circuit 55 will then be completely broken and the motor brought to a stop. When again necessary to start the engine the switch arm is further rotated again to bring it into the position of Fig. 1 when the operation will 60 be repeated. 35 indicates a retaining nut threaded to the end of the shaft 2 to limit the movement of the pinion.

In Fig. 3 I have shown a simple modification of the previous arrangement wherein 65 the initial effect of retarding the pinion 8

to secure the movement of the operating spline relative to the pinion, is accomplished by the shifting of the armature. As shown, the armature 1 is journaled normally to be displaced from its field under the influence 70 of a retractile spring 40; the bearings and commutator being sufficiently elongated therefor. Upon establishing the initial engaging circuit through the resistance *r* the armature will be shifted into its field against 75 the pressure of the spring 40, thereby carrying with it the operating collar 18 and the pinion 8, the latter being brought into partial or retarding engagement with the fly-wheel gear 12. Thereafter on the rotation 80 of the armature the pinion positively will be shifted into full engagement with the gear 12. Upon the kicking out of the pinion by starting of the engine, as described, the circuit will be completely broken owing to 85 the shifting of the ring 32 and the retractile spring 40 will then displace the armature to complete the disengaging of the pinion.

In Figs. 4 to 7 I have illustrated a further modified embodiment of my invention 90 adapted to a motor wherein the armature is shifted to provide the complete movement for engaging the pinion and gear. As there shown, the armature is arranged to be displaced under the action of a retractile spring 95 40' confined between a collar 42, held against the frame *f* thereby, and a collar 43 on the armature shaft 2. The collar 42 is rotatively connected to the armature shaft by a key fitted to a suitably elongated key-slot 44 in 100 the shaft. Upon the collar, insulated therefrom, is supported a copper contact ring 46 having a laterally extended contact projection or lip 48. Said ring 46 is arranged constantly to be engaged by the brush 33. On 105 the hub 19 of the pinion 8, keyed on the end of the shaft, is a similar copper contact ring 50 having a contact lip 51 projecting in a plane and toward the lip 48 to be in overlying engagement therewith when the pinion 110 is in driving engagement as shown in Figs. 5 and 6.

As shown in Figs. 6 and 7 the pinion 8 is keyed on the armature shaft 2 by a key 54 on the shaft fitted to an enlarged key slot 55 115 in the pinion hub 19. By this arrangement it will be seen that a partial rotative movement of the pinion with reference to the shaft 2 is permitted. While the armature shaft is exerting a driving pressure on the gear 12, through the pinion, the key 54 will assume a position engaging at the forward end of the key slot 55, as shown in Fig. 6, and the contact lips 48 and 51 are arranged then to be in radial alinement to complete 120 the work circuit through their respective rings 46 and 50 and brushes. However, on the acceleration of the gear 12, by starting of the engine, it will turn the pinion 8 with 125 relation to the shaft 2 to the position shown 130

in Fig. 7, moving the contact 51 circumferentially with relation to contact 48 whereby they are separated to break the circuit. The engagement of the key will then be at 5 the rear of the slot 55.

Upon the motor circuit being so broken the spring 40' will force the pinion 8 out of engagement, likewise moving the motor armature into the initial displaced position 10 of Fig. 4. When the motor is again energized by moving the switch S around to the starting position of Fig. 4, the contacts 48 and 51 will again be brought into radial alinement so that they will make engagement 15 when the pinion is moved into operative engagement.

To promote the introduction of the gears I have indicated an arrangement whereby the magnet initially will receive the full 20 current to exert its maximum energy in shifting the pinion while less than the maximum current is passed through the motor armature to reduce the rotative effort. This consists in a connection 60—60' from the 25 battery connected to the field coils as shown to short circuit the armature. The connection 60—60' is arranged to be broken at contacts 61—62 and the switch arm S carries an auxiliary arm 64 to close the circuit 30 through the connection 60—60' in the first position of arm S. The magnetic pull is thus strengthened to insure of shifting the pinion in the first position of the switch arm while the armature receives a reduced energizing current to reduce the rotative effort. 35 On advancing the switch to the second position indicated in Fig. 5, the circuits through connections 25 and 60—60' are broken and with the pinion in proper engagement the 40 armature will receive the full working current from the battery.

It will be understood that in some of the claims which follow, I use the expressions "initial driving circuit connections" and 45 "full driving circuit connections," and by these expressions I mean respectively the circuit connections which cause the motor to operate initially prior to enmeshment and the circuit connections which cause the 50 motor to operate with full power to perform the actual cranking operation.

Having described my invention, I claim:

1. An electrical starting device for internal combustion engines, comprising in combination with a motor, a connector element shiftable by the motor to couple the motor and the engine for starting of the latter, and means actuated by the motor and carried by the connector element to close the driving 55 circuit only when the connector element is in proper engagement with the engine and to maintain said circuit closed during the starting operation.

2. A starter for engines comprising in 60 combination with a rotatable shaft sup-

ported at its inner end and a driving member which is mounted on the shaft to have longitudinal movement thereof and a rotary movement therewith, said member being normally adjacent the outer end of the 70 shaft but movable inwardly when the shaft is rotated, a battery, circuit connections including an initial driving circuit and a full driving circuit for connecting said battery with said starter, a switch for controlling 75 the initial circuit connections, and contact members having sliding connection with one another and controlled by said starter for closing the full driving circuit connections to cause the torque operation of the 80 starter.

3. An electrical starting device for internal combustion engines comprising in combination with a motor; a connecting gearing adapted to couple the motor and engine together on starting; and contact means carried by the connecting gearing for automatically closing the driving circuit only when the gearing is in proper connecting position, maintaining said circuit closed 90 during the starting operation, and opening said circuit after the engine is running.

4. In combination with an engine; a starting motor therefor; a helix connected with said motor; a pinion movable on said 95 helix; a battery; circuit connections between said battery and motor; a toothed member connected with the engine and adapted to be engaged by said pinion; and circuit-controlling means for delaying the 100 full application of power to said pinion, until said pinion is fully connected with the engine, said means controlled by the position of said pinion.

5. In combination with an engine, a starting motor therefor; a helix connected with said motor; a pinion movable on said helix; a toothed member connected with the engine for engagement by said pinion; a battery; circuit connections between said battery and motor including a resistance element; means for closing a circuit connection through said resistance element to initiate the starting operation; and automatic means actuated by the movement of 110 the pinion for closing another circuit connection which connects the motor directly with the battery to apply the full power of 115 the motor to start the engine.

6. In combination with an engine; a starting motor therefor; a toothed member connected with the engine; a pinion connected with the motor and shiftable by said motor into engagement with said toothed member; a battery; circuit connections between said 120 battery and motor including a resistance element; means for closing the circuit connection through said resistance element to initiate the starting operation; and automatic means including contact members 125 130

having sliding engagement one of which is carried by the pinion for closing another circuit connection which connects the motor directly with the battery to apply the full power of the motor to start the engine.

7. An electrical starting device for internal combustion engines comprising in combination with a motor, a connector element adapted to couple the motor and the engine 10 for starting of the latter, a battery, an initial driving circuit connection and a full driving circuit connection between said battery and said starting device; and automati-

cally operative means including coöperating annular contact and brush contact members for closing the full driving circuit connection when the gears are in proper engagement. 15

In testimony whereof I have signed my name to this specification in the presence of 20 two subscribing witnesses.

J. ROSCOE MILLWARD.
